UNITED STATES PATENT OFFICE.

HALVOR A. LUND, OF WARREN, ARIZONA.

COMBINATION COMB AND BRUSH.

1,386,344.

Specification of Letters Patent. Patented Aug. 2, 1921.

Application filed July 22, 1920. Serial No. 398,069.

To all whom it may concern:

Be it known that I, HALVOR A. LUND, a citizen of the United States, residing at Warren, in the county of Cochise and State 5 of Arizona, have invented certain new and useful Improvements in Combination Combs and Brushes; and I do hereby declare the following to be a full, clear, and exact description of the invention, such as will enable others skilled in the art to which it applies 10 to make and use the same.

My invention relates to new and useful improvements in combination devices and more particularly to a combination comb 15 and brush, and the primary object of the invention is to provide a device of this character which will simplify the use of both elements and which will at the same time enable either element to be used independently 20 of the other.

A further object resides in providing a device which will enable the device to be used with one hand, thereby permitting the hair to be brushed and combed at one and the 25 same time.

Still another object resides in providing a device which is simple in construction and inexpensive to manufacture, and which will enable the user to carry the same in the 30 pocket of his clothing, as he would an ordinary comb.

With these and other objects in view, my invention consists in the novel features of construction, combination, and arrangement 35 of parts as will be hereinafter referred to and particularly pointed out in the specification and claims.

In the accompanying drawings, forming a part of this application,

40 Figure 1 is a perspective view of the most simple form of my invention,

Fig. 2 is a similar view showing a slightly different form thereof, the comb being folded in position against the brush, and

45 Fig. 3 is a similar view showing the comb extended and ready for use in connection with the brush.

In describing the invention I shall refer to the drawing in which similar reference 50 characters designate corresponding parts throughout the several views and in which 1 designates a flat back for a brush, said back being of any desired size and mounted therein are the bristles 2. The bristles do not 55 cover the entire width of the back 1 of the brush, leaving an open space in the back

which may be designated in the drawings as 2^a. Secured to the side edge of the back 1 most remote from the bristles 2 is a comb 3, the same being secured to the back by means 60 of screws or other adjustable means designated as 3^a and in securing the comb to the back of the brush it will be observed that the teeth 4 of the comb are arranged to project to a plane even with the plane of the ends 65 of the bristles 2.

It will be seen that this combination device may be used by the operation of one hand so that the hair may be combed and brushed at one and the same time. However, the space between the comb and the 70 bristles which I have designated in the drawing as 2^a enables the device to be tilted so that either the comb or the bristles of the brush may be used independently.

75 In Figs. 2 and 3 I have shown a slightly modified form of the invention wherein a brush 5 is provided which is preferably of reduced width. Secured to the one side face of the back of the brush 5 is a hinge 80 leaf 7 and hinged to the leaf 7 is an additional hinge leaf 8, the leaf 8 being capable of being swung to a position as shown in Fig. 3 or to a position as shown in Fig. 2, as indicated by the dotted arc 9. A comb 6 is 85 provided which is so constructed as to be hinged as shown at 10 to the outer edge of the leaf 8. The comb 6 is so hinged that when it is in the position as shown in Fig. 3 90 the upper edge thereof will abut the inner side face of the leaf 8 to prevent folding of the comb inwardly against said leaf, but the comb 6 may be folded outwardly against the outer face of the leaf, as shown in Fig. 2. Thus, when it is desired to carry the device 95 in the pocket the leaf 8 is folded against the side of the brush 5 and the comb 6 folded against the outer side of the leaf 8, as shown in Fig. 2 of the drawings. When it is desired to place the device in use, it is only 100 necessary to extend the leaf 8 to a horizontal position and fold the comb 6 downwardly with respect thereto, bringing the complete device to a position as shown in Fig. 3. The device may then be used for both brushing 105 and combing the hair by a single operation of one hand and inasmuch as the comb 6 remains spaced from the bristles of the brush, it will be seen that the possibility of using the comb 6 or the brush independently is 110 at the will of the user.

The brush head 5 and the comb 6 are

gripped by a person with the leaf 8 resting against the palm of the hand thereby preventing the leaf from swinging upwardly or downwardly in respect to the brush.

5 From the foregoing, it will be seen that I have provided a simple, inexpensive and efficient means for carrying out the object of the invention and while I have described the elements best adapted to perform the 10 functions set forth, it will be understood that various changes in form may be made in accordance with the scope of the appended claims.

Having thus described my invention what 15 I claim is:—

1. A device of the class described comprising a brush including a back and bristles depending therefrom, and a comb hinged to

the one side edge of said back and adapted to be positioned in spaced relation to the 20 bristles when set for use.

2. A device of the class described comprising a brush including a back and bristles depending therefrom, an extension hinge secured to the one side edge of said back and 25 a comb pivoted to said hinge and adapted for folding against the side of said brush and also for extension to a position in spaced relation to the aforesaid bristles.

In testimony whereof I affix my signature 30 in presence of two witnesses.

HALVOR A. LUND.
